UNITED STATES PATENT OFFICE.

BENJAMIN LAVIANO, JOSEPH ALESSE, AND SALVATORE CAMPAGNA, OF SAN JOSE,
CALIFORNIA.

SHOE STRETCHER.

Application filed July 18, 1927. Serial No. 206,585.

It is the object of the invention to provide a stretcher for leather shoes that will apply pressure uniformly to the upper and side portions of the toe and adjoining parts to 5 stretch the same simultaneously.

It is another object of the invention to provide a device of the character indicated that will be simple in construction, economical to manufacture, and highly efficient in its 10 practical application.

In the drawings:

Figure 1 is a plan view of the device, part being broken away.

Figure 2 is a side elevation of the device, 15 part broken away.

Figure 3 is a side elevation of the device as shown in Figure 2 with one side element removed.

Figure 4 is an inside side elevation of one 20 of the side elements of the device.

Figure 5 is an enlarged perspective view of the device with part removed and partly in section.

Figure 6 is a section on line 6—6 of Figure 25 2.

Figure 7 is a side elevation of the spreader shoe.

Referring now more particularly to the drawing, we show at 1 a base element, oblong 30 in general formation and flat on the bottom but having an upstanding boss on one end of its upper surface as at 2. A distance forwardly of the part 2 the element increases in thickness to form a cam surface 3, and 35 longitudinally of this upper surface and in the median line thereof is formed a cam slot 4, the bottom surface thereof sloping downwardly from its front to its rear end as indicated. This element is widened somewhat 40 laterally as at 5 and terminates at its forward end in a toepiece 6 provided with shoulders 7. Upon the rear end of element 1 is mounted a resilient plate 8 extending a distance thereabove.

45 At 9—9 are shown two side elements having their outer surfaces shaped to the general formation of the shoe on their outer sides, each element having a groove 10 formed longitudinally thereof and in its inner surface as shown. These elements are mounted upon the plate 8 as at 11, this plate being their only support.

50 A top piece is shown at 12, this piece being also mounted at its rear end upon the resilient plate 8 and having a pair of for-

wardly projecting fingers 13 mounted upon its forward end by means of resilient straps as 14. One of these straps is mounted in a recess 15 on each side of element 12 and is seated in a similar recess in the side of 55 the adjoining finger 13. This construction causes the fingers to move as a unit with the element 12 and yet they may be spread laterally at the same time. A socket 16 is formed in the under side of element 12 and 60 crosswise thereof near its point of attachment to plate 8. A socket is also formed in the under side of element 12 and at right angles to socket 16 to receive an operating element as hereinafter described, this socket 65 being indicated at 17. Formed in the bottom 70 of element 12 and communicating with the socket 17, is a recess 18 open at its forward end, and formed in the bottom of fingers 13 and communicating with the recess 18 is a 75 tapering channel 19. This channel narrows from both the sides and top as it approaches the forward ends of the fingers to form cam surfaces for the purpose hereinafter set forth, and as indicated at 20, 21, 22. The 80 bottom of the top piece and the fingers is flat, but since the upper surface of the bottom or base is provided with a cam surface it results that when the device is assembled there is a space between the parts 85 throughout approximately one-half their length as clearly shown in Figure 3.

At 23 we show a shoe adapted to seat in recess 18 and tapering somewhat forwardly as at 24 to readily enter into and engage the channel 19. Extending laterally from the shoe 23 are wings as 25 provided with laterally extending pins 26 adapted to engage the grooves 10 in the side elements 9—9. Depending from the under side of the shoe 90 is a keel 27 adapted to engage the slot 4 in part 1. To the rear end of this element is connected a threaded operating rod 28 by means of a swivel joint at 29. On the rod 28 is mounted an element 30 having laterally extending pins 31 adapted to engage the socket 16 as shown.

It is obvious that with the construction above described the side elements 9—9 and the top piece 12 with fingers 13 are normally 105 held in close contractual relationship with each other so as to present a solid form having substantially the same outer conformation as the shoe to be stretched. When the device is inserted in a shoe in the usual man-

ner and the rod 28 rotated the shoe 23 and parts connected thereto is moved forwardly. This forward movement is effected by means of the threaded engagement of the rod with the element 30 which is held against movement by its position in the socket 16. As the shoe moves forwardly it engages the channel 19, and since this is tapering in form it gradually forces the two parts 13 to 10 spread outwardly against the tension of the spring elements 14. At the same time the keel 27 is advancing in slot 4 which forces the shoe upwardly and thereby raises the part 12 and parts carried thereby by against the tension of the spring plate 8. At the same time that these actions are taking place the pins 26 are moving forwardly in grooves 10 in side elements 9 thereby forcing them outwardly and upwardly against the tension of resilient plate 8. It will be noted that the part 12 with its fingers 13, and 9—9 have a pivotal movement due to their single attachment at their rear ends, and since the spreader, comprising parts 23 to 27, is positioned intermediate the plate 8 and the forward end of the stretcher the forward ends of the said parts are spread at the very point where the shoe is to be stretched. Furthermore, by means 20 of this device the shoe is stretched laterally and upwardly at the same time thereby securing the desired result quickly and effectively.

It is to be understood, of course, that 35 while we have herein shown and described but one specific embodiment of the invention, changes in form, construction and method of assembly and operation may be made within the scope of the appended claims.

40 We claim:

1. A shoe stretcher comprising a base, an upstanding resilient plate mounted on one end thereof, a pair of opposed spreader elements connected to the plate and normally 45 paralleling the sides of the base, a spreader element mounted on the top of the base and connected to said plate, and means for spreading the elements against the tension of the resilient plate.
- 50 2. A shoe stretcher comprising a base element, opposed side elements movably connected thereto and normally paralleling the sides thereof, a top spreader element connected thereto and overlying the base be-

tween the said side elements and movable 55 relative to the base, means for simultaneously moving the side elements upwardly and outwardly from the base and the top element upwardly from the base, and resilient means for returning the elements to their 60 normal positions.

3. A shoe stretcher comprising a base, two opposed side elements and a top element resiliently connected at their corresponding ends to one end of said base, a pair of laterally swingable fingers resiliently mounted on said top element and lying between said side elements, and an element mounted on the base and movable longitudinally thereof adapted to engage said side elements, 70 top and fingers to move the same outwardly against their resilient mountings.

4. A shoe stretcher comprising a base, a top member resiliently mounted thereon at one end and having a pair of laterally swingable fingers resiliently mounted upon its opposite end, a shoe slidably mounted on the said base beneath said top and fingers, and cam surfaces formed on said base, top and fingers whereby a movement of the shoe in 80 one direction will move the top element upwardly, and the fingers upwardly and outwardly with respect to the base.

5. A shoe stretcher comprising a base member having a slot formed along the 85 median line of its upper surface, a shoe having laterally extending pins and a keel to slidably engage said slot, opposed side elements resiliently connected at their corresponding ends to one end of the base and having grooves formed in their opposed sides to engage the pins on said shoe, a top element resiliently mounted at one end to the end of the base adjacent the connections 90 of the side elements and having a recess formed in its under surface to receive said shoe and having a pair of fingers extending forwardly from its other end and resiliently connected thereto to swing laterally, the 95 said fingers having a channel formed in their under surfaces to receive said shoe and tapering forwardly whereby a forward movement of the shoe therein will effect lateral swinging movement, and operating means for the shoe.
